UNITED STATES PATENT OFFICE

153,184

DESIGN FOR A VEHICLE LAMP

Benjamin H. Smith, Kansas City, and Wilbur P. Peterson, Independence, Mo., said Smith assignor to said Peterson

Application March 15, 1948, Serial No. 145,096

Term of patent 7 years

(Cl. D48—32)

To all whom it may concern:

Be it known that we, Benjamin H. Smith and Wilbur P. Peterson, citizens of the United States, residing at Kansas City and Independence, respectively, in the county of Jackson and State of Missouri, have invented a new, original, and ornamental Design for Vehicle Lamp, of which the following is a specification, reference being had to the accompanying drawing, forming part thereof.

Fig. 1 is a perspective view of a vehicle lamp, showing our new design.

Fig. 2 is a front elevational view of the vehicle lamp.

Fig. 3 is a plan view of the vehicle lamp.

Fig. 4 is a side elevational view of the vehicle lamp.

We claim:

The ornamental design for a vehicle lamp, as shown.

BENJAMIN H. SMITH.
WILBUR P. PETERSON.
